UNITED STATES PATENT OFFICE.

ISAAC S. WOOD, JR., OF ELBERFELD, INDIANA.

THRESHING-MACHINE FEEDER.

SPECIFICATION forming part of Letters Patent No. 746,429, dated December 8, 1903.

Application filed June 30, 1903. Serial No. 163,777. (No model.)

To all whom it may concern:

Be it known that I, ISAAC S. WOOD, Jr., a citizen of the United States, and a resident of Elberfeld, in the county of Warrick and State of Indiana, have invented a new and Improved Threshing-Machine Feeder, of which the following is a full, clear, and exact description.

This invention relates to improvements in feeders for threshing-machines, the object being to provide a feeder of simple construction having no parts liable to get out of order and so arranged as to feed evenly from the top of the bundles.

I will describe a threshing-machine feeder embodying my invention and then point out the novel features in the appended claim.

Reference is to be had to the accompanying drawings, forming a part of this specification, in which similar characters of reference indicate corresponding parts in both the figures.

Figure 1 is a sectional elevation of a portion of a threshing-machine, showing the feeder embodying my invention; and Fig. 2 is a side elevation thereof, taken in the opposite direction.

In the drawings, 1 designates an endless conveyer arranged in the casing 2. This conveyer extends around rollers 3 4, and its upper stretch passes over an idler 5. Arranged over the inner end of the conveyer is an endless feeding-apron 6, which extends at its outer end around a roller 7 and at its inner end passes over a roller 8, the ends of the shaft of said roller 8 being extended through vertically-disposed slots 9 in the opposite side walls of the casing. By this arrangement the inner portion of the feeder is permitted a vertically-swinging movement, the object of which will hereinafter appear. The shafts of the rollers 7 8 are connected at the outer sides of the casing by arms 10, and from one of the extended ends of the shaft for the roller 8 a rod 11 is extended to a connection with a lever 12, mounted to swing on the outer side of the casing and having a forked lower end for engaging in an annular channel formed in the hub portion of a friction-disk 13, mounted to slide on a shaft 14, but rotating therewith. The disk 13 engages peripherally with a friction-disk 15, on the shaft of which is a sprocket-wheel 16, having a

chain engagement 17 with a double sprocket-wheel 18 on the shaft of a band-cutter 19. Also extended from one set of teeth of the sprocket-wheel on the shaft of the band-cutter is a chain 20, engaging with a sprocket-wheel 21 on the shaft of the roller 7, and this roller 7 may be connected by a chain or band with a wheel on the shaft of the threshing-cylinder 22. The shaft 14 has a bevel-pinion 23, which engages with a bevel-pinion 24 on the shaft of the roller 4.

In the operation it is to be understood that the conveyer 1 has a much slower motion than the feeding-apron 6, and the speed of motion of said conveyer is variable. As a bundle of straw is placed on the conveyer it passes underneath the band-cutter 19, where the band is severed. Then it passes to the feeding-apron 6. This feeding-apron 6 will be moved upward in accordance with the thickness of the bundle and will scrape off layers from the top thereof and pass the same to the cylinder 22. As the inner end of the apron 6 moves upward it will rock the lever 12 to move the disk 13 outward from the center of the disk 15, thus causing a very slow movement of the conveyer 1 and preventing its moving the whole bundle of straw to the threshing-cylinder. As the thickness of the bundle diminishes the inner end of the feeding-apron 6 moves downward, consequently moving the disk 13 toward the center of the disk 15, thus increasing the speed of the conveyer. At certain times—that is, when the disk 13 is at the center of the disk 15—the conveyer will remain stationary. This only occurs, however, when an extra large bundle is placed in the machine.

With an automatic feeding mechanism embodying my invention the grain, as before stated, will be evenly fed in layers to the threshing-cylinder, and therefore there will be but very little, if any, jar to the machinery, as is the case when whole bundles are fed to the cylinder.

Having thus described my invention, I claim as new and desire to secure by Letters Patent—

In a threshing-machine, a feed mechanism comprising an endless conveyer, an endless feeding-apron, arranged over the inner end

of said conveyer, a vertically-movable roller around which the apron passes, a shaft having gear connection with the roller around which the conveyer passes, a friction-disk 5 movable lengthwise of said shaft but rotating therewith, a friction-disk operated from the feed-apron and engaging with the first-named disk at right angles thereto, a rod extended from said vertically-movable roller,

and a swinging-lever connection between said rod and the first-named disk.

In testimony whereof I have signed my name to this specification in the presence of two subscribing witnesses.

ISAAC S. WOOD, JR.
